(57) **CLAIM**

We claim the ornamental design for an LED acrylic conduit, as shown and described.

DESCRIPTION

An LED acrylic conduit light fixture having the shape of a semi-circular cylinder with quarter-spherical ends from the apical surface of which extends a parallel smaller semi-circular cylinder with quarter-spherical ends.

FIG. 1 is an overall perspective view of the ornamental design of the present invention.

FIG. 2 is a top view of the ornamental design of the present invention.

FIG. 3 is a side view of the ornamental design of the present symmetrical invention.

FIG. 4 is a front view of the ornamental design of the present invention.

FIG. 5 is a back view of the ornamental design of the present invention; and,

FIG. 6 is a bottom view of the ornamental design of the present invention.
